ABSTRACT OF THE DISCLOSURE

A method for reducing zearalenone to zearalanol in which the product contains a major amount of the high-melting diastereoisomer and a minor amount of the low-melting diastereoisomer of zearalanol is disclosed. Zearalenone is catalytically reduced with hydrogen for a time sufficient to reduce the zearalenone to zearalanol in the presence of a platinum catalyst and a weak acid having a first acid ionization constant of from about 1×10^{-4} to 5×10^{-1} in water at about 25° C. and said acid not being itself reduced under the conditions of the zearalenone reduction.

This invention relates to a method for reducing zearalenone to a mixture of the high- and low-melting point diastereoisomers of zearalanol.

The terms "zearalenone" and "zearalanol" conform with the nomenclature in an article in *Tetrahedron Letters*, Pergamon Press, Ltd., No. 27, pp. 3109-3114 (1966). When zearalenone, having the formula

is converted to zearalanol, having the formula

by reduction of the olefinic bond and the ketone group in the presence of hydrogen, a mixture of diastereoisomers of zearalanol is formed. This reduction, carried out in the presence of a Raney nickel catalyst, is disclosed in U.S. Pat. No. 3,239,345. The diastereoisomers differ in melting point. The disclosed reduction provides an approximately 55:45 ratio of the high-melting point to the low-melting point diastereoisomer.

Disclosed in U.S. Patent application Ser. No. 25,265, filed Apr. 2, 1970, now U.S. Pat. 3,697,548, and in corresponding Belgium Pat. No. 765,130, is a method of catalytically reducing zearalenone to a mixture containing a major amount of the diastereoisomer of zearalanol having the higher melting point and a minor amount of diastereoisomer of zearalanol having the lower melting point in the presence of a strong acid, that is, an acid which is essentially completely ionized in an aqueous solution. This process, while producing a good conversion of zearalenone to the diastereoisomer of zearalanol having the higher melting point with a relatively rapid rate of conversion, requires reaction vessels which are extremely resistant to strong acids or requires frequent replacement of reaction vessels due to corrosion.

It was also disclosed in United States patent application Ser. No. 25,265, now U.S. Pat. No. 3,697,548, and corresponding Belgium Pat. No. 765,130, that a weak acid, e.g., acetic acid, was found unsatisfactory for promoting the reduction of zearalenone to the high boiling diastero-

2

isomer of zearalanol. For example, acetic acid only provides about a 15 to 20 percent reduction of zearalenone to zearalanol after a six hour reaction period.

The product can be separated utilizing a procedure disclosed in Examples I and II of U.S. Pat. No. 3,574,235 in the name of Vernon V. Young. Both diastereoisomers of zearalanol are useful as anabolic substances for oral and parenteral administration to animals in the manner disclosed in U.S. Pat. No. 3,239,345.

10 It has now been found that certain weak acids may be employed in a process for the catalytic reduction of zearalenone to a mixture containing a major amount, e.g., greater than 55 weight percent, for example, about 60 weight percent or more, of the diastereoisomer of zearalanol having the higher melting point and a minor amount, e.g., less than 45 weight percent, for example, about 40 weight percent or less, of the diastereoisomer of zearalanol having the lower melting point.

In accordance with the present invention, the reduction of zearalenone is conducted in the presence of a solvent, a platinum catalyst, and certain weak acids for a time sufficient to reduce the zearalenone to zearalanol and provide a high ratio of the high melting point diastereoisomer to the low melting point diastereoisomer. The product will generally contain a major amount of the high melting point diastereoisomer of zearalanol. The weak acid employed in the process of the present invention has a first acid ionization constant of from about 1×10^{-4} , preferably 5×10^{-4} to 5×10^{-1} in an aqueous solution at 25° C., and will not itself be reduced to a weaker acid under the conditions employed for the zearalenone reduction.

20 The term "weak acid," as used herein, refers to acids which are less than essentially completely ionized in water (except in extremely dilute solution). It conforms with standard nomenclature as found in, for example, *Fundamental Concepts of Chemistry*, Appleton-Century-Crofts (1969), pp. 233 and 234. Such weak acids include weak acids as well as moderately strong acids. Exemplary of 25 the weak acids which may be employed in the present invention are citric acid, tartaric acid, phosphoric acid, and oxalic acid.

30 The zearalenone can be prepared and purified as described in Examples II and III of U.S. Pat. No. 3,239,345. The zearalenone is advantageously suspended or dissolved 35 in a suitable solvent, preferably a lower alkanol, e.g., ethanol, normal propyl alcohol, isopropyl alcohol and the like, preferably those containing from 1 to 3 carbon atoms and particularly ethanol. Zearalanol-producing amounts 40 of a weak acid, often a small amount, e.g., about 0.001 to 5 volume percent (based on the solvent), preferably from about 0.01 to 3 volume percent or equivalent weight, of weak acid is added to the solvent. The reaction may be conducted in the presence of, for instance, about 2 to 10 volume percent of water.

45 The zearalenone and solvent can advantageously be present in amounts of, for example, from about 1 to 25 grams of zearalenone per 100 cc. of the solvent. A platinum catalyst supported on a suitable carrier, e.g., charcoal, is advantageously used. Generally, the catalyst contains 50 from about 0.01 to about 10 weight percent of platinum and is employed in catalytic amounts, generally a catalyst to zearalenone weight ratio of from about 0.001:1 to 1:1.

55 The zearalenone is reduced in the presence of hydrogen under reducing conditions for a time sufficient to reduce 60 substantially all of the zearalenone. Advantageously, the reduction can be carried out at a temperature of from about 15° to 100° C., preferably about 20 to 60° C. with a hydrogen pressure generally of from about 20 to 1000 p.s.i., preferably 25 to 100 p.s.i., for at least 3, preferably 65 about 3 to 8, hours. After the reduction, the platinum cata-

lyst is removed from the reaction mixture, e.g., by filtration, and the resulting mixture can, as a matter of convenience, be concentrated, to say, a volume of from about 0.5 to 0.1 of the reaction mixture volume, and filtered again. The filtered, concentrated solution can be diluted with water, for example, in an amount of from about 2 to 4 volumes of the concentrated solution, by adding water slowly while stirring the solution. The resulting solution is advantageously allowed to stand at room temperature for a time sufficient to allow the zearalanol to precipitate from the solution which can be about 2 to 4 hours or more. Filtration of the mixture yields the white crystals of zearalanol containing a major amount of the high melting diastereoisomer and a minor amount of the low melting diastereoisomer which can be separated as noted above.

The following examples are presented to further illustrate the invention and are not in limitation thereof.

EXAMPLE I

Three grams (g.) of zearalenone and 3 milliliters of 85% phosphoric acid are added to 200 ml. of ethanol at room temperature, and, after flushing with nitrogen, 1.0 g. of a 5 percent platinum on charcoal catalyst is added. The solution is charged into an Adams reducing apparatus and reduced with hydrogen for 6 hours at room temperature under a hydrogen pressure of 50 p.s.i. The resulting reduced mixture is filtered, concentrated to 75 ml. and filtered again. Then, 400 ml. of water are added to the mixture slowly with stirring. After 3 hours at room temperature, the mixture is filtered to give 2.61 g. of zearalanol which is analyzed to be about 76% of the high melting diastereoisomer and 24% of the low melting diastereoisomer.

EXAMPLES II TO IX

The following examples were conducted in essentially the same procedure as that set forth in Example I except different solvents and weak acids are employed. The results of these examples are set forth in Table I.

TABLE I

Example	Solvent	Weak acid	Amt., g.	Time, hrs.	Amount zearalanol recovered as percent of zearalenone charged	Ratio of high melting diastereoisomer, percent
II	Ethanol	Tartaric	2	7	86	75
III	do	do	2	8	84	77
IV	Isopropanol	do	2	7	72	72
V	t-Butanol	Phosphoric	2	7	82	62
VI	Ethanol	Oxalic	2	7	86	73
VII	do	Citric	2	7	83	74
VIII	do	Succinic	2	7	(1)	-----
IX	do	Maleic	2	7	(1)	-----

¹ Product obtained in mostly zearalanone

Examples I to VII illustrate the advantageous conversion of zearalenone to zearalanol which can be achieved using the process of the present invention even using simple methods for recovering the zearalanol from the reaction solution. In comparison, Examples VIII and IX disclose the use of weaker acids in essentially the same process. Succinic acid has an ionization constant of about 6.6×10^{-5} at 25°C . in an aqueous solution. Maleic acid, which is a relatively strong weak acid, is reduced under the conditions of the reaction to succinic acid, and hence, the results obtained are comparable to that of Example VIII.

It is claimed:

1. A method for reducing zearalenone to a mixture of a major amount of the high melting point diastereoisomer and a minor amount of the low melting point diastereoisomer of zearalanol comprising catalytically reducing zearalenone with hydrogen under reducing conditions in the presence of zearalanol-producing amounts of a weak acid and catalytic amounts of platinum catalyst, said weak acid having a first acid ionization constant of from about 1×10^{-4} to 5×10^{-1} in aqueous solution and said weak acid not itself being reduced to a weaker acid under the reducing conditions.
2. The method of claim 1 wherein the reducing conditions include temperatures from about 15° to 100°C . and a hydrogen pressure from about 20 to 1000 p.s.i. and the catalyst is employed in a catalyst to zearalenone weight ratio from about 0.001:1 to 1:1.
3. The method of claim 2 wherein the reduction is conducted in the presence of a solvent consisting essentially of a lower alkanol.
4. The method of claim 3 wherein the lower alkanol contains from 1 to 3 carbon atoms and the solvent contains from about 0.001 to 5 volume percent (based on the solvent) of the weak acid.
5. The method of claim 2 wherein the catalytic reaction is carried out with reducing conditions including temperatures from about 20 to 60°C . and a hydrogen pressure from about 25 to 100 p.s.i.
6. The method of claim 3 wherein the solvent contains weak acid in an amount from about 0.01 to 3 volume percent, based on the volume of the solvent.
7. The method of claim 2 wherein the reduction is conducted in the presence of water in an amount of about 2 to 10 volume percent.
8. The method of claim 1 wherein the weak acid has a first acid ionization constant of from about 5×10^{-4} to 5×10^{-1} .
9. The method of claim 2 wherein the weak acid is tartaric acid.

55 10. The method of claim 2 wherein the weak acid is phosphoric acid.

11. The method of claim 2 wherein the weak acid is oxalic acid.

60 12. The method of claim 2 wherein the weak acid is citric acid.
